UNITED STATES PATENT OFFICE.

GEORGE J. KAUTZ, OF EMPORIUM, PENNSYLVANIA.

CIRCULAR SAWING MACHINE.

SPECIFICATION forming part of Letters Patent No. 293,037, dated February 5, 1884.

Application filed December 14, 1883. (Model.)

To all whom it may concern:

Be it known that I, GEORGE J. KAUTZ, of Emporium, in the county of Cameron and State of Pennsylvania, have invented a new and Improved Sawing-Machine, of which the following is a full, clear, and exact description.

My invention consists in certain improvements in that class of circular sawing machines in which the saw-frame is automatically swung into position by a cam, and the feed-roller is also automatically operated, as will be herein-after set forth and claimed.

Reference is to be had to the accompanying drawings, forming part of this specification, in which similar letters of reference indicate corresponding parts in all the figures.

Figure 1 is a plan view of my improved cut-off saw, with part *c* of the table-top removed. Fig. 2 is a transverse section of the machine 20 on the line *xx* of Fig. 1. Fig. 3 is a section on line *yy*, Fig. 1.

The circular cut-off saw *a* is arranged on the swinging frame *b* under the table *c*, as is usual in such machines, to swing up in front of the feed-rolls *d e*, to cut off boards, which are fed along over the saw by the said feed-rolls, when the saw is swung down below the surface of the table. The frame *b* is fixed on a pivot at *f*, on which there is a pulley, *g*, from which a belt runs to the pulley *h* on the saw-arbor *i*, said pulley *g* being driven by a belt from the large pulley *j*, or from any other approved driver.

To raise the saw automatically, I arrange a cam-shaft, *k*, under the saw-frame *b*, with a cam, *l*, on it acting against the under side of the saw-frame, and gear the said cam-shaft *k* with the shaft *m* of the driving-pulley *j* by the pinion *n* on the shaft *m* gearing with the large wheel *o* on the cam-shaft, by which the saw-frame will be raised up and let fall once for each revolution of the cam, which is properly speeded for the purpose; and to feed up the stuff to be sawed automatically also, I fix another cam, *p*, on the shaft *k*, and set oppositely to cam *l* to act on a lever, *q*, which is pivoted to the frame at *s*, and is connected at its free end with an endless chain, *t*, running over an idler, *u*, and also over a loose pulley, *v*, on the shaft of the lower feed-roll, *d*, and having a ratchet, *w*, attached to it, which ratchet en-

gages the pawl *x* when the lever *q* is raised by the cam *p*, and turns the feed-roll forward, the pawl *x* being connected to a disk, *y*, that is keyed to the shaft of the feed-roll. When the lever *q* falls, the pulley *v* and ratchet *w* are shifted back preparatory for another forward movement.

The pawl *x* is pivoted to the disk *y* at *z*, and has a spring, *a'*, to hold it in contact with the pawl for the forward movement, and to yield and allow the pawl *x* to escape from the notches of the ratchet when the ratchet turns back. The weight of the lever *q* causes said lever to shift the ratchet back.

By the arrangement of the cams *l* and *p* opposite to each other the saw rises when the feed mechanism is reversing, and the feed mechanism works when the saw is down. I also propose to arrange the upper feed-roll, *e*, 70 in a swinging frame, *b'*, mounted on pivots at *d'* above the feed-table *e'*, to enable said upper feed-roll to shift up and down according as the stuff to be sawed varies in thickness, and will make said frame sufficiently heavy to press the 75 stuff down on the lower feed-roll, so as to insure the feeding of it properly by the lower feed-roll. Both of said feed-rolls are to be armed with pointed disks *f'*, for adhesions to the wood.

A rope may be substituted for the chain *t* by 80 connecting one end with lever *q*, passing the rope under roller *u*, thence up over pulley *v*, and thence downward, with a weight hanging by it to produce the required tension; but the lever must be heavier than the weight to pull 85 the ratchet back.

Having thus fully described my invention, I claim as new and desire to secure by Letters Patent—

1. The combination, with the lever *q*, pivoted 90 at *s* to the frame, and connected at its free end to the chain *t*, which passes under an idler below the lever, and over a chain-pulley on the shaft of the feed-roller *d* above the lever *q*, of the cam *p*, mounted on shaft *k*, for operating lever *q*, and devices connected therewith, substantially as described.

2. The combination of the feed-roller *d*, on the shaft of which is mounted loosely a chain-pulley, *v*, having secured thereto a ratchet-disk, *w*, and also a disk rigidly secured to said shaft *d*, and carrying a spring-pawl, with the chain *t*,

idler u , and pivoted cam-operated lever q below the table, substantially as set forth.

3. The combination of the shaft k , provided with the cams l p , the former for operating the swinging saw-frame and the latter for operating the pivoted lever q , connected with the chain t , passing under idler u and over loose chain-pulley v , on the shaft of the feed-roller d , with the fixed disk on said shaft carrying the fixed ratchet w and its spring-pawl, and suitable gearing for operating the shaft k and the saw, substantially as set forth.

4. The combination of the shaft k , carrying

the cams l p , mounted, respectively, below the swinging saw-frame and pivoted lever g , and 15 said shaft k , also provided with cog-wheel o , with the shaft m , provided with pinion n , gearing with wheel o , and with a driving-pulley for operating said shaft m and the pulleys g h on the saw-frame shaft and saw-arbor, respectively, by belts passing over the same, substantially as set forth.

GEORGE J. KAUTZ.
